United States Patent Office

Des. 178,277
Patented July 17, 1956

178,277

SCHOOL DESK

Charles F. Close, Arlington Heights, Ill., assignor to Arlington Seating Co., Arlington Heights, Ill., a corporation of Illinois

Application May 11, 1955, Serial No. 35,917

Term of patent 14 years

(Cl. D33—11)

FIG. 1

FIG. 4

Fig. 1 is a side elevational view of a school desk, embodying my new design;

Fig. 2 is a rear elevational view thereof;

Fig. 3 is a front elevational view thereof; and
Fig. 4 is a top plan view thereof.

I claim:

The ornamental design for a school desk, as shown.
